UNITED STATES PATENT OFFICE.

JULIA BRANDENSTEIN, OF BROOKLYN, NEW YORK.

DESIGN FOR A HAT.

SPECIFICATION forming part of Design No. 23,653, dated September 25, 1894.

Application filed August 3, 1894. Serial No. 519,397. Term of patent 7 years.

To all whom it may concern:

Be it known that I, JULIA BRANDENSTEIN, a citizen of the United States, residing at Brooklyn, in the county of Kings and State 5 of New York, have invented a new Design for a Hat, of which the following is a specification.

The leading feature of this design relates to the shape of the band and ear covers, the 10 band being parallel and the ear covers having compound curved edges the curved edges starting at and extending downwardly from the band.

In the drawing the design of the hat is represented by a perspective view.

The crown portion *a* projects and is corrugated or plaited and the band *b* has nearly parallel top and bottom edges except at the ear covers the edges of which at the junction with the band are curved at *c* and made with 20 a reverse or compound curve at the lower edges *d*.

I claim—

The design for a hat as described and shown. Signed by me this 31st day of July, 1894.

JULIA BRANDENSTEIN.
